US00D843388S

(12) **United States Design Patent** (10) **Patent No.:** **US D843,388 S**
Protzman et al. (45) **Date of Patent:** **** Mar. 19, 2019**

(54) **DISPLAY SCREEN OR PORTION THEREOF
WITH SET OF GRAPHICAL USER
INTERFACES**

(71) **Applicant:** **Lutron Electronics Co., Inc.**,
Coopersburg, PA (US)

(72) **Inventors:** **Brent Protzman**, Easton, PA (US);
Michelle L. Greene, Bethlehem, PA
(US); **Erica L. Clymer**, Northampton,
PA (US); **Jennifer Wong**, Breinigsville,
PA (US); **Stephen Lundy**, Coopersburg,
PA (US); **Samuel F. Chambers**,
Gwynedd Valley, PA (US)

(73) **Assignee:** **Lutron Electronics Co., Inc.**,
Coopersburg, PA (US)

(**) **Term:** **15 Years**

(21) **Appl. No.:** **29/642,635**

(22) **Filed:** **Mar. 30, 2018**

Related U.S. Application Data

(63) Continuation of application No. 29/586,976, filed on Dec. 8, 2016, now Pat. No. Des. 814,501, which is a continuation of application No. 29/525,146, filed on Apr. 27, 2015, now Pat. No. Des. 777,199.

CLAIM

The ornamental design for a display screen or portion thereof with set of graphical user interfaces, as shown and described.

DESCRIPTION

The sole FIGURE shows two portions of a display screen with set of graphical user interfaces showing our new design.

The dashed broken lines illustrate a display screen or portion thereof, and form no part of the claimed design.

The bracket indicates a set of graphical user interfaces, and forms no part of the claimed design. The graphical user

(Continued)

interfaces are arranged, as shown for convenience of illustration; the relative arrangement of graphical user interfaces forms no part of the claimed design.
